US0D1025891S

(12) **United States Design Patent** (10) **Patent No.:** **US D1,025,891 S**
(45) **Date of Patent:** **** May 7, 2024**

(54) **BATTERY CHARGER HOUSING**

(71) Applicant: **Zhengyun Hua**, Chuzhou (CN)

(72) Inventor: **Zhengyun Hua**, Chuzhou (CN)

(**) Term: **15 Years**

(21) Appl. No.: **29/908,701**

(22) Filed: **Jan. 15, 2024**

(30) **Foreign Application Priority Data**

Oct. 23, 2023 (EM) 015037970-0001

(51) **LOC (14) Cl.** **13-02**
(52) **U.S. Cl.**

USPC **D13/119**; D13/107; D13/184

(57) **CLAIM**

The ornamental design for a battery charger housing, as shown and described.

DESCRIPTION

FIG. 1 is a front, left, and top perspective view of a battery charger housing, showing my new design;

FIG. 2 is a rear, right, and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines depict portions of the battery charger housing that form no part of the claimed design.
